NUMERAL CLOCK

Frank G. Almquist, Mount Vernon, N. Y.

Application January 29, 1935, Serial No. 3,932

4 Claims. (Cl. 58—125)

My present invention relates to clocks, and more particularly to an improved clock of the "numeral" type.

In my present invention I have dispensed with the usual and ordinary dial having numerals printed, stamped, embossed, etched, lithographed or otherwise marked on or attached to its facial periphery, and with which cooperate hour, minute and/or second hands for indicating visually the time, and in place thereof utilize a plurality of rotatable members mounted on a common, and preferably horizontal, axis. These rotatable members are each provided with a plurality of plates, on each of which are formed, or attached, a numeral or numerals designating the hours, tens of minutes, and minutes respectively, and adapted to be brought into registry to designate and indicate the time as determined by the operating means therefor.

I am aware that numeral clocks, per se, are old, and therefore make no broad claim to such a construction. Such former numeral clocks however, have had of necessity, numerals of such small size as to render the same practically illegible when viewed from even a comparatively short distance, unless the entire mechanism is of such size as to be cumbersome and unsightly.

In order to obtain the largest size numerals possible, and at the same time keep the mechanism as small as possible, I preferably use rotatable number plates, each plate being provided with two numbers, one on one face, and one on the other face. For example, where six plates are used to designate the hours, one of such plates will have the numeral "1" on one face, and the numeral "7" on the other face. The numeral "7" is arranged in transposed relation to the numeral "1" so that each may be in proper position to be read when brought into time indicating position. It will be readily seen that such an arrangement results in a numeral twice the size of the numeral heretofore ordinarily employed on the usual types of cylindrical or polygonal shaped numeral carrying drums, and this without increasing the size of the mechanism.

In carrying out my invention, I advantageously place the number indicating time, on both faces of the number plates, and in order to bring the numbers thereon successively into registry to indicate time by hours, tens of minutes and minutes, I preferably arrange the appropriate ones of such number plates to be rotated about an axis which is parallel to but independent of the

axis of rotation of the rotatable member carrying the same.

With a view to keeping all the units (i. e., minutes, tens of minutes, and hours) as near the same size as possible, I preferably construct the number plates representing the tens of minutes to be non-rotatable, the numerals of such tens of minutes being displayed on one face only of said plates.

As a modification of my invention, while maintaining the rotatable feature of the number plates, I cut the numerals through the material of the number plates. This construction enables me to illuminate the numbers from the rear by any suitable means, as an electric light, and the rotatable character of the number plates, independent of the rotation of the carrying means therefor, permits the easy relamping of same.

While in the above referred to modification of my invention, the cutting of the numbers through the material of the plates results in reducing the size thereof to approximately one half the area of the facial surface of the number plates, this is more than overbalanced by the fact that light from the source of illumination is projected through the numbers onto a translucent plate, causing obviously the numbers to appear in enlarged form on said translucent plate. The number visible on the plate through this method of projection can be made, with ease, double the size of the actual numeral as cut in the plate.

During the period of change, which occurs each minute in the case of the minute number, each ten minutes in the case of the tens of minutes, and each hour in the case of the hour, the circuit of the lamp for illuminating the numerals may be automatically opened if desired, to extinguish the light, and is again automatically closed when the period of change is over.

An object of my invention is an improved numeral clock.

Another object is an improved numeral clock in which the numerals indicating the time are of large size as compared with the size of the clock.

Still another object of my invention is an improved means for illuminating the time indicating numerals in a numeral clock.

A further object is an improved driving mechanism for numeral clocks and the like.

Other objects and novel features of the construction and arrangement of parts comprising my improved clock will appear as the description of the invention progresses.

In the accompanying drawings,

Fig. 1 is a front elevation of a clock embodying my invention;

Fig. 2 is a section on the line 2—2 of Fig. 1;

Fig. 3 is a front elevation of the complete mechanism removed from the casing shown in Figs. 1 and 2;

Fig. 4 is a section substantially on the line 4—4 of Fig. 2;

Fig. 5 is a section on the line 5—5 of Fig. 3;

Fig. 6 is a section on the line 6—6 of Fig. 3;

Fig. 7 is a section on the line 7—7 of Fig. 3;

Fig. 8 is an enlarged section on the line 8—8 of Fig. 3;

Fig. 9 is a perspective view of the hour indicating rotatable number plates and the mounting therefor.

Fig. 10 is a view, similar to Fig. 2, and showing a modified form of my invention in which the numbers are cut through the material of the number plates, and

Fig. 11 is a plan view of the type of number plate employed in the modification shown in Fig. 10.

Referring to the drawings, 10 designates a clock case mounted on a base 11, and provided with a sight or opening 12 through which numerals, indicating the time, may be viewed. The sight or opening may be free and unobstructed, or may be provided with a protecting member 15, as shown in Fig. 2, of clear glass, or other equivalent transparent material, and through which the numerals on the surfaces of the rotatable number plates may be viewed. If desired, the faces of the number plates may be illuminated by light from an electric lamp 14, as shown in Fig. 2.

Within the case 10, and secured to the base 11 in any convenient manner, is a base plate 17, on which the operating mechanism, and the structure comprising my invention, are mounted.

On the top of the base plate 17, and arranged parallel to but spaced apart from each other, are secured the bearing plates 18 and 19. Secured in and extending between the bearing plates 18 and 19 is a bearing shaft 20. On the shaft 20, adjacent to the bearing plate 18, is rotatably mounted a sleeve 21. Secured to the sleeve 21, adjacent to the plate 18, is a pinion 22 which periodically meshes with and is driven by a segmental gear 23 secured to and rotating with the drive shaft 24 of a synchronous motor 25.

The synchronous motor 25 is of the usual type and comprises a base plate 26 and supporting spaced hollow standards 27, through which pass the body portion of screws 28, said screws clamping the usual magnet system 29 in position and screwing into threaded holes in the plate 18. Secured to the base 26 and magnet system 29 is the casing 30 containing the operating mechanism and through which the drive shaft 24 extends. The synchronous motor 25 is so designed as to have the drive shaft 24 make one complete revolution every 60 seconds, or each minute.

The sleeve 21 is provided with a flange 31, and on the sleeve 21, between the flange 31 and the pinion 22, is securely fastened a disc 32 and a disc-like member 33 occupying a position between the disc 32 and the pinion 22. Adjacent to the periphery of the disc 32 and extending laterally outward from the disc toward the pinion 22 is a stud 34 and, referring to Fig. 5, it will be noted that the disc-like member 33 is cut away at 35 to allow a space between the stud 34 and the cutaway portion 35.

Arranged parallel to the shaft 20 and fastened

in a perforation in the plate 18 and in a similar perforation in an auxiliary plate 36 is a shaft 38, on which and adjacent to the plate 18 is rotatably mounted a sleeve 39. The plate 36 is secured to the base 11 by screws 37.

At the end of the sleeve 39, adjacent to the plate 18, is formed a shoulder 40, and secured to the shoulder 40 and to the sleeve 39 is a Geneva wheel 41. Referring to Fig. 5 it will be noted that this Geneva wheel 41 is divided into six segments separated by radially extending slots 42, the slots being of a width to slidably engage with the laterally extending stud 34 on the disc 32 above referred to. The outer perimeter of each of the segments of the Geneva wheel 41 is recessed, as indicated by the reference numeral 43, on an arc whose radius is equal to the radius of the disc-like member 33 above referred to. In Fig. 5 the laterally extending stud 34, on the disc 32, is shown as just coming into one of the radially extending slots 42 on the Geneva wheel 41, and the recessed portion 43 is shown as engaging with the periphery of the disc-like member 33.

The shaft 24 of the synchronous motor 25 rotates in the direction of the arrow on the segmental gear 23, causing an intermittent rotary movement of the disc 32 and disc-like member 33 in a clockwise direction, and therefore an intermittent rotary movement of the Geneva wheel 41 in a counterclockwise direction, as noted by the arrow on such Geneva wheel.

Secured to the sleeve 21 and the flange 31, and lying parallel to the disc 32 and disc-like member 33 is a disc 45. At spaced points about and adjacent the periphery of the disc 45 are arranged perforations normal to the disc 45, and in each of which is secured a bearing sleeve 46. For the purposes of the present invention the number of perforations, and therefore the number of bearing sleeves 46, is five, such bearing sleeves being equally spaced as shown in Fig. 5. Rotatably mounted in each of the sleeves 46 and being prevented from accidental removal therefrom by any desirable means, is a shaft 47. The shafts 47 have secured to the end thereof, remote from the end adjacent to the disc 32, a hub 48. Each of such hubs 48 have secured to the outer face thereof in any convenient manner, as by a slot, a number plate 49, such number plate 49 being symmetrically arranged, as far as regards the ends thereof, and printed or engraved on the number plate 49, or on a card attached thereto is a number 44, the numbers running from 0 to 9.

Diametrically arranged on the hub 48 and on each side of the number plate 49 are notches 50, adapted to be engaged by a detent 51 formed on the free end of a spring catch 52, which has its other end secured to the disc 45 by a rivet or screw 53. The spring catch 52 is relatively light in weight and while it normally holds the number plate 49 normal to a diameter passing through the centers of the shafts 47 and 20, will permit rotary movement of the shaft 47 and therefore the number plate 49 without the expenditure of an appreciable amount of energy.

Referring to Figs. 5 and 8 it will be noted that the overall length of the number plates 49 is so proportioned with regard to the diameter of the disc 45 that when such number plates 49 are in their normal position, that is, in a position normal to a diameter passing through the shafts 47 and 20, the ends of such number plates 49 extend slightly beyond the periphery of the disc 45.

Secured to the base 11 by screws 54 and ex-

tending upwardly from the base 17 to a point adjacent to the periphery of the disc 45 is a standard 55, provided adjacent to its top end with a laterally extending pin 56 which extends into the path of movement of the extending ends of the number plates 49. As the disc 45 rotates in the direction of the arrows shown in Fig. 8, it is obvious that the lowermost extending end of the number plate 49 shown at the left of the standard 55 will be engaged by the laterally extending pin 56, and as the disc 45 continues its rotation, a rotary movement about the shaft 47 in a clockwise direction will be imparted to such number plate 49.

15 In Fig. 8 there is shown in dot and dash lines the intermediate turning position of the lefthand number plate as it will be turned during the rotation of the disc 45. Assuming the disc 45 in Fig. 8 to have rotated from the position shown in 20 full lines to the position where the lefthand number plate 49 occupies the intermediate position shown in dot and dash lines in such figure, it is obvious that as the rotation of the disc 45 continues the lower half of the number plate 49 will 25 ride over the pin 56 to continue the rotative movement of such plate, and which rotative movement will continue until the detent 51 on the spring catch 52 drops into the appropriate groove 50 in the hub 48, or into the position now occupied by the detent 51 on the right hand hub 48.

20 Formed on the sleeve 39, and spaced apart from the shoulder 40, is a shoulder 58, and secured to the sleeve 39 and the shoulder 58 is a disc 59, provided at equally spaced points on its 25 face adjacent to its periphery with three laterally extending studs 60. Secured to the sleeve 39 and to the disc 59 is a disc-like member 61. The disc-like member 61 is provided with three laterally extending portions each occupying a space midway between adjacent laterally extending pins 60 on the disc 59, as shown in Fig. 6.

25 Rotatably mounted on the shaft 20 and spaced from the sleeve 21 by a sleeve 62, is a sleeve 63, this sleeve 63 at the end adjacent to the sleeve 40 62 being provided with a shoulder 64. Secured to the sleeve 63 and the shoulder 64 is a Geneva wheel 65 provided with a plurality of slots 66, six in number, and of a width to slidably accommodate the laterally extending studs 60 on the disc 59. The periphery of the Geneva wheel 65 between adjacent radial slots 66 is as indicated by the reference numeral 67 in Fig. 6, in the form of concave arcs of a radius equal to the radius of the convex arcs of the outer periphery of the 35 three projections on disc-like member 61, and referring to Fig. 6 it will be noted that one of the studs 60 has just come into one of the radial slots in the Geneva wheel 65.

30 As the sleeve 39 is intermittently rotated in the manner above described, and in the direction of the arrows shown in Fig. 6, it will be obvious that the Geneva wheel 65, and therefore the sleeve 63, will be intermittently rotated in the direction of the arrows shown on such Geneva wheel 65 in Fig. 6. The sleeve 63 has secured thereon adjacent to the Geneva wheel 65, but spaced therefrom by the washer 68, a disc 69 which on the face thereof adjacent to the periphery thereof is provided with a plurality—six in number—of 35 equally spaced perforations and in each of which is secured a bearing sleeve 46. The bearing sleeves 46 in the disc 69 are similar to the bearing sleeves 46 in the disc 45, and the shafts 47, hubs 48, and associated parts shown in detail in Fig. 8 40 and described above, find their counter part in

the structure shown and carried by the disc 69. It is sufficient to say therefore, that on the hubs 48 that are carried by the disc 69, there are number plates 70 similar in character to the number plates 49 above referred to, and on each of such 45 number plates 70 is provided a numeral indicating the tens of minutes.

Because of the fact that the number plates 70 carry the tens of minutes numerals, and because there are six such tens of minutes in an 10 hour, there is no necessity for the number plates 70 being rotated, and therefore the counterpart of the turning pin 56 of Fig. 8 is not associated with the disc 69.

15 It has been pointed out above that the seg- 15 mental gear 23 is mounted on the drive shaft 24 of the synchronous motor 25 and imparts an intermittent rotary movement to the pinion 22, and as the drive shaft 24 of such synchronous motor 25 makes one complete revolution for 20 each minute of elapsed time, it is obvious that an intermittent rotary movement is imparted to the pinion 22 once for each minute. The number of teeth on the segmental gear 23 bears such a relation to the number of teeth in the pinion 22 25 that the pinion 22 is rotated through one fifth of a revolution for each minute of time, and therefore one of the numbers on each of the plates 49 is brought into registry with the sight opening 12 in the casing 10 once each minute. The 30 disc 45 will therefore make one complete revolution for every five minutes of time.

35 The sleeve 39 having secured thereto the Geneva wheel 41, and the Geneva wheel 41 having six radial slots 42, and such radial slots being engaged in succession once per each five minutes of time by the laterally projecting pin 34 on the disc 32, the sleeve 39, and therefore the disc 59 will be rotated through one-sixth of a revolution 40 for each five minutes of time. As, however, there are but three laterally extending pins 60 on the disc 59, there will be imparted to the Geneva wheel 67 a rotary movement through one-sixth of a revolution for every one-third revolution of the disc 59. In other words, the Geneva wheel 67, 45 and therefore the disc 69, will make one-sixth of a revolution for each ten minutes of time, and therefore the numerals on the plate 70 carried by the disc 69 will be brought successively into registry with the sight opening 12 in the casing 10 50 at intervals of ten minutes apart.

55 On the sleeve 63, which is rotatably mounted on the shaft 20, and adjacent to the end thereof remote from the shoulder 64, is a shoulder 71. Secured to the sleeve 63 and shoulder 71 is a disc 72, provided on one face thereof adjacent to the periphery with a laterally projecting stud 73. On the shaft 38 is rotatably mounted a sleeve 74 60 provided with a shoulder 75. Secured to the sleeve 74 and shoulder 75 is a disc-like member 76. The disc 76 is provided with a plurality of equally spaced radial slots 77, six in number, adapted to engage with as a sliding fit the laterally extending stud 73 on the disc 72. Secured to the base 17 by screws 78 is a spring catch 57, the outer free end of which is adapted to engage with the radial slots 77 in succession to maintain the disc-like member 76 in adjusted position 70 against accidental movement. Secured to the sleeve 74, adjacent to but spaced slightly apart from the disc-like member 76, is a disc 79 provided on the face remote from the disc-like member 76, and adjacent the periphery, with a plu- 75

rality of laterally extending studs 80, six in number.

5 Rotatably mounted on the shaft 20, adjacent to the sleeve 63, is a sleeve 81 to which is fastened a disc-like member 82 provided with a plurality of radially extending slots 83 adapted to slidably engage or be engaged by the laterally extending studs 80 on the disc 79. The number of slots 83 is six, being equal in number to the number of 10 laterally extending studs 80 in the disc 79.

15 Also secured to the sleeve 81 is a disc 83a provided with a plurality of laterally extending bearing sleeves 46, these sleeves being identical with the corresponding sleeves above described as being carried by the discs 45 and 69 respectively. Associated with such sleeves 46 are the hubs 48 provided, as in the construction referred to and illustrated in Fig. 8 with the diametrically opposed grooves 50 and with the spring members 20 52 carried by the disc 83a and associated therewith. Each of the hubs 48 carries a number plate 84.

25 Secured to the base 17 by screws 85 is a standard 86 carrying at its top end a laterally extending pin 87 which lies in the path of movement of the ends of the plates 84, it being understood, as was the case with respect to the plates 49 carried by the disc 45, that the length of the plates 84 bears such a relation to the circumference 30 of the disc 83a that the ends of the plates 84 extend outwardly beyond the circumference of the disc 83a.

35 Referring to Fig. 11 there is shown a plate 88 in which numerals are cut through the body of the plates, each plate 88 carrying two numbers as shown, one readable from one side of the plate and the other number from the other side. Referring to Fig. 10 there is shown a plurality of plates 88 carried on a disc 89, and illuminated 40 by a lamp 90.

45 It has been pointed out above that the disc 69 rotates through one-sixth of a revolution for each 10 minute interval of time, therefore bringing the numerals of the plates 70 into registry with the sight opening 12 in the casing 10. As the disc 72 rotates with the disc 69, and as the disc 72 carries but a single laterally projecting stud 73 it is obvious that the disc 76 containing the radial slots 71 with which the laterally projecting stud 73 engages will be rotated through one-sixth of a revolution for each complete revolution of the disc 69. As however, the disc 79, rotating with the disc 76 and at the same rate of speed, has six equally spaced laterally projected studs 80 and as there are six radially extending slots 71 in the disc-like member 76, it is obvious that the disc 83a will rotate through one-sixth of a revolution for each one-sixth of a revolution of the disc-like member 76. The disc 83a therefore rotates through one-sixth of a revolution for each hour interval of time.

55 In the case where the numerals in the various number plates 49, 70 and 84 are cut out of the material of such plates, I find it preferable to place a source of illumination in the rear of each plate as the same is brought into registry with the sight opening 12 in the casing 10 and such form of illumination preferably takes the form of an electric light bulb 90 carried by a standard 91 and to 60 which power is transmitted from any suitable source. Such a source of illumination is employed as shown in Fig. 10, together with the translucent sight covering member 13 and on which the numerals are projected and made visible. Where 65 however, the numerals in the various number

70 plates are impressed or engraved on the surface of the various plates the translucent member 13 has substituted therefore preferably a clear glass cover member 15 for the sight opening 12 and a source of illumination 14 in the form of an electric bulb is placed in the corner of the casing 10 as shown in Fig. 2 to illuminate the visible face of the number plates, and thereby render numbers engraved or impressed thereon visible to the observer through the clear glass closure member 15.

75 The driving mechanism for the various minutes, tens of minutes, and hour discs has been described in detail and such construction has been found exceedingly efficient, requiring a minimum of power and one that does not place an immoderately heavy load on the driving motor. The details of construction however, of such driving mechanism may be varied at will and I am not to be limited to the exact details of construction as 20 above illustrated and described except as herein-after pointed out in the appended claims.

80 My invention has been described as applied to a time keeping mechanism, where the time is indicated by a plurality of interconnected members each carrying numerals and which numerals are periodically brought into registry to indicate the time by hours, tens of minutes, and minutes. The numerals are relatively large as compared to the size of the mechanism, and are actually twice as 30 large as in prior numeral clocks.

85 My invention however, is applicable to other devices than direct reading time keeping clocks, and may be utilized in calendar devices and in similar situations where definite results are to be 35 produced in predetermined sequence.

90 I am not therefore, to be limited to time keeping devices other than as pointed out in the appended claims.

I claim:

1. In a numeral clock, the combination with a driving mechanism, a plurality of members arranged side-by-side associated with the driving mechanism, and interconnected to be intermittently and rotatably driven at predetermined 45 times to measure time in minutes, tens of minutes and hours, a plurality of bearings arranged on each of said plurality of members adjacent to the circumferential edge thereof, shafts rotatably mounted in each of said bearings, number of 50 plates secured to said shafts, numbers on said plates occupying the larger portion of the superficial areas of each face of said plates, and means including said driving mechanism for rotating the said shafts to successively bring the numbers on 55 opposite faces of the plates into viewing position.

2. In a numeral clock, the combination with a driving mechanism, a plurality of rotatably mounted members interconnected together, arranged side by side and intermittently rotated by 60 said driving mechanism in timed relationship to each other, a plurality of number plates associated with each of said rotatably mounted members, said number plates being less in number than the numbers to be indicated thereby, a mounting for each of said number plates comprising a bearing mounted on the rotatably mounted members, a shaft rotatably mounted in the bearing, means for securing the number plate to the shaft, numbers on both faces of said number plates, said 65 numbers each of a size substantially equal to the larger portion of the superficial area of the faces of said number plates, and being large as compared to the size of the complete clock, and means for successively engaging the number plates dur- 70

ing the intermittent rotation of the rotatably mounted members for rotating said number plates and to successively bring the numbers on the opposite faces thereof into viewing position.

3. In a numeral clock, the combination with a driving mechanism, a plurality of rotatably mounted members interconnected together, arranged side by side and intermittently rotated by said driving mechanism in timed relationship to each other, a plurality of number plates, less in number than the numbers to be indicated thereby, numbers on both faces of said number plates, said numbers each of a size substantially equal to the larger portion of the superficial area of the faces of said number plates, and being large as compared with the size of the complete clock, a mounting for each of the number plates, each said mounting comprising a bearing secured to the rotatably mounted members, a shaft rotatably mounted in each said bearing, means for securing each of the number plates to its respective shaft, and means for successively engaging each said number plate during a step in the intermittent rotation of the rotatably mounted members

carrying the same for successively rotating said plates through an angle of 180°.

4. In a numeral clock, the combination with a driving mechanism, a plurality of rotatably mounted members interconnected together, arranged side by side, and intermittently rotated by said driving mechanism in timed relationship to each other, a plurality of number plates, less in number than the numbers to be indicated thereby, said number plates each rotatably and independently mounted on the rotatably mounted members on an axis symmetrical with the area of the number plates, means for successively engaging said number plates during a step in the intermittent rotation of the rotatably mounted members for rotating said plates through an angle of 180°, a translucent window arranged parallel to the number plates when the same are in viewing position, said translucent window being spaced apart from the number plates, and means for projecting light through the numbers on the number plates and projecting the image of said numbers onto the translucent window. 10 15 20

FRANK G. ALMQUIST.
